BATHROOM SCALE

Vytant Aleks, Rockford, Ill., assignor to The Brearley Company, Rockford, Ill., a corporation of Illinois

Filed Jan. 25, 1962, Ser. No. 68,516

Term of patent 14 years

(Cl. D52—10)

FIG. 1 is a perspective view of a bathroom scale incorporating my new design;

FIG. 2 is a plan view with the dial indicia omitted;

FIG. 3 is a side view;

FIG. 4 is a rear view;

FIG. 5 is a sectional detail on a larger scale at either of the four places indicated by the line 5—5 in FIG. 2;

FIG. 6 is a similarly enlarged sectional detail on the line 6—6 of FIG. 2, and

FIG. 7 is a similarly enlarged sectional detail on the line 7—7 of FIG. 2.

The sectioning for plastic material in FIGS. 5, 6 and

7 represents clear transparent plastic material through which the rest of the platform of the scale is visible, and the surface shading on this part of the scale in FIGS. 1 to 4 also indicates the transparency.

I claim:

The ornamental design for a bathroom scale, substantially as shown and described.
